APPARATUS FOR COOKING BRIQUETS.

1,037,479.

Specification of Letters Patent. Patented Sept. 3, 1912.

Application filed July 21, 1911. Serial No. 639,861.

To all whom it may concern:

Be it known that I, PAUL HEIN, a subject of the King of Prussia, residing at Essen-Ruettenscheid, in the Kingdom of Prussia, German Empire, have invented certain new and useful Improvements in Apparatus for Coking Briquets, of which the following is a specification.

The present invention has for its object an improved apparatus or kiln for coking or roasting briquets that have been compressed from small coke or coal in which a binding medium preferably soluble in water is employed and which require a heating to be carried as far as coking the binding medium so that the latter might assume a form resisting water.

In my improved kiln the molded briquets while being continuously rotated and turned are carried down by drums arranged in superposition, these drums being heated by means of hot air, furnace gases or the like, whereby the briquets are gradually roasted in being carried down to the lower portion of the kiln, that is through the hottest heat zone. Dividing this operation the hot gases pass through the perforated walls of the drums and blow over the briquets. In this manner the briquets are exposed during their entire passage through the kiln continuously and alternately on all sides to the direct action of the hot furnace gases and thereby are subjected to a vigorous gradually increasing drying action by the heat which is produced, and maintained during the operation by the supply of furnace gases throughout the entire room in which the drums are arranged and which with the exception of the gas discharge flue and the supply and delivery passages is completely closed.

The drawings illustrate a kiln with two superposed drums but if desired, three or more drums may be employed in a vertical series.

Figure 1 is a transverse section of the kiln and Fig. 2 a similar section at right angle to Fig. 1.

In the casing *a* which is preferably constructed of masonry drums *b* and *b'* are rotatably arranged in superposition. These drums have a perforated periphery furnished with radially directed scoop-like walls *c* spaced apart so as to form radial

compartments or chambers *d* for the reception of the briquets to be roasted. The partitions of the compartments or chambers *d* can be formed of continuous or perforated metal plates. The lengths of the drums *b* and *b'* can vary as desired and they can be divided into two or more compartments *f* by means of disk like walls *e* which together with the end walls *e'* of the drums are fixed to the axles *s* and *s'* positively connected by a gearing, such as sprocket wheels *t*, *t'* and a chain *t'*, and duly supported in bearings *u* in the wall of the casing *a*. In order to prevent the briquets from prematurely falling out of the separate compartments or chambers *d* of the drums *b* and *b'* during the rotation of the latter, guide walls *g* and *g'* are provided and these walls as shown surround a portion of the periphery of the drums *b* and *b'* and carry or support the briquets during part of their travel around the drum axis. The guide walls *g* and *g'* are also perforated in order to afford a free passage for the ascending hot air through the separate chambers *d* of the drum *b* or *b'*.

h is a passage or chute for supplying the briquets to be coked or roasted to the uppermost drum and which can be regulated as desired by means of a slide *i* or the like.

k is an intermediate slide channel or chute through which the briquets leaving the chambers or compartments *d* of the upper drum *b* pass to the chambers or compartments of the lower drum *b'* in which they are carried around while being heated by the ascending hot gases which in this part of the casing *a* have a higher temperature than in the upper part where the upper drum is located. From the drum *b'* the briquets are delivered and pass through the passage or chute *m* to a conveyer *n*. The hot air is supplied to the kiln through the conduit *o* which is adapted to be regulated by means of a slide *p* or the like.

t is the discharge flue.

Partitions *q* may be provided corresponding to the intermediate walls *e* of the drums in order to keep the current of hot air divided in the vertical direction so that it must pass uniformly and positively through the two compartments *f* of the drums.

The coking of the briquets proceeds as

follows: The briquets are fed to and pass through the supplying chute h into the compartments d of the upper drum b . Owing to the rotation of the drum b around its axis in the direction of the arrow (Fig. 1) produced by any suitable motor and intermediate driving means through the aid of the sprocket wheels t t' the briquets contained in the compartments d are carried through the upper part of the shaft of the casing a and pass through the chute k in a preliminarily dried or roasted condition to the next lower drum b' which carries the briquets through a lower level of the shaft in which the hot gases ascending from the supply pipe o are of a higher temperature than in the upper part of the shaft so that the briquets continuously in contact with the ascending current of hot air become fully roasted. This procedure of conveying the briquets through the ascending hot air in a direction counter to the path of the hot air during a length of time that can be predetermined by the number of superposed drums and by the speed of rotation of the drums, insures a complete roasting or coking of the binding medium. From the lowest drum the completely roasted briquets slide through the chute m to the conveyer n .

The bottom plate k' of the chute k is by means of a hinge k^2 or otherwise pivotally connected to the wall g , so as to be adjustable to any desired angle and the cross-sectional area of the chute at the lower end of the plate k' can separately be regulated by means of a slide r or the like.

What I claim as my invention is:

1. Apparatus for coking or roasting briquets, comprising a plurality of superposed drums having perforated walls and provided with radial compartments adapted to receive the briquets, a chute for delivering the briquets to the top drum, an intermediate chute for conveying the briquets to the next lower drum, a discharge chute in connection with the lowermost drum, a conduit at the bottom of the apparatus for supplying the drying and heating medium, and

a perforated guide below each drum for supporting the briquets in the drum.

2. Apparatus for coking or roasting briquets, comprising a plurality of superposed drums having perforated walls and provided with radial compartments adapted to receive the briquets, a chute for delivering the briquets to the topmost drum, an intermediate chute for conveying the briquets to the next lower drum, a discharge chute in connection with the lowermost drum, a hot air supply at the bottom of the apparatus, and an adjustable slide in said intermediate chute.

3. Apparatus for coking or roasting briquets, comprising a plurality of superposed drums having perforated walls and provided with radial compartments adapted to receive the briquets, a chute for delivering the briquets to the topmost drum, an intermediate chute for conveying the briquets to the next lower drum, a discharge chute in connection with the lowermost drum, a hot air supply at the bottom of the apparatus, a perforated curved guide plate below each drum for supporting the briquets therein, and an adjustable slide in said intermediate chute.

4. Apparatus for coking or roasting briquets, comprising a plurality of superposed drums having perforated walls and provided with radial compartments adapted to receive the briquets, a chute for delivering the briquets to the top drum, an intermediate chute for conveying the briquets to the next lower drum, a discharge chute in connection with the lowermost drum, a conduit at the bottom of the apparatus for supplying the drying and heating medium, and a perforated guide below each drum for supporting the briquets in the drum, and a conveyer in connection with said discharge chute.

In testimony whereof I have affixed my signature in presence of two witnesses.

PAUL HEIN.
